UNITED STATES PATENT OFFICE.

JOSEPH H. BRADY, OF KANSAS CITY, MISSOURI.

AIR-LINE EXHAUSTER FOR STEAM-HEATING SYSTEMS.

1,290,703.

Specification of Letters Patent.

Patented Jan. 7, 1919.

Application filed February 3, 1916. Serial No. 76,003.

To all whom it may concern:

Be it known that I, JOSEPH H. BRADY, a citizen of the United States, residing at Kansas City, in the county of Jackson and

5 State of Missouri, have invented certain new and useful Improvements in Air-Line Exhausters for Steam-Heating Systems, of which the following is a specification.

My invention relates to air line exhaustors for steam heating systems, and the invention embodies means for alternately introducing steam and water, or their equivalents, into a vacuum tank to create a sufficient vacuum therein for the purpose of 15 drawing the air from the heating system.

My object is to provide a simple and inexpensive apparatus of the character referred to, and one which is reliable and economical in operation and can be maintained 20 at small expense.

In order that the invention may be fully understood, reference will now be made to the accompanying drawings, in which:

Figure 1 is a diagram of the apparatus 25 connected up ready for use.

Fig. 2 is a vertical section of the vacuum tank and adjacent parts.

Fig. 3 is a vertical section of a self-opening valve for admitting steam to the vacuum 30 tank.

Fig. 4 is a broken sectional view of a self-closing valve for controlling the admission of water to the vacuum tank.

Fig. 5 is a vertical, central section of a 35 governor employed in carrying out the invention.

Fig. 6 is a vertical section of a manually-operable valve.

Fig. 7 is a vertical section of a check 40 valve.

Fig. 8 is a vertical section of a thermostat.

A designates the radiator of a steam heating system to which my apparatus is con-

45 nected for the purpose of exhausting air therefrom. B designates an air line pipe for conducting air from the radiator A, the flow of air from the latter to the former being automatically controlled by a thermostatic valve D. The pipe B communicates with a vacuum line E leading to the top of the vacuum tank 1.

50 The vacuum line E is provided with a gate valve F and a check valve G, which former is manually closed when it is desired to cut off communication between the radiator A

and the vacuum tank 1 and stop the action of the apparatus, while the latter is designed to automatically close and relieve the vacuum line E of back pressure from the tank 60 1, should the intermittent pressure in the latter exceed that in said vacuum line. A vacuum gage H, communicates with the vacuum line E to indicate the extent of the vacuum within said vacuum line and the vac- 65

uum tank 1.

2 designates a water supply pipe extending into the tank 1 through a plug 3 and provided at its inner end with a spray nozzle 4. The flow of water through said supply pipe 2 is manually controlled through a gate valve 5, and automatically controlled by a self-closing valve 6. The pressure of the water in the supply pipe 2 is indicated by a water gage 7, communicating there- 75

8 designates a steam pipe communicating with the vacuum tank 1 and leading from a suitable source of supply, not shown. The pressure of the steam is indicated by a steam 80 gage 8^a communicating with the steam pipe 8. The flow of steam through the pipe 8 is manually controlled by a gate valve 9 and automatically controlled by a governor 10 and a self-opening valve 11. The governor 85 10 is closed by vacuum in the tank 1 with which it communicates through a pipe 12, and may be of any suitable type, but I prefer to employ the one disclosed in my co-pending application Serial No. 37,192. 90

The valves 6 and 11 are actuated by fluid under pressure consisting, preferably, of air leading from a compressed air tank 13 through pipes 14, 15, 16, and 17, which latter two communicate, respectively, with the valves 6 and 11. The flow of air from the pipe 15 into the pipe 16 is automatically controlled by a thermostat 18, which extends into the vacuum tank 1 and is controlled by the temperature therein. Said governor 10 100 consists, preferably, of a valve 24, a resilient bellows 25 for normally holding said valve 24 in open position, a coil spring 26 and a nut 27 for regulating the tension of the bellows 25. The interior of the bellows 25 105 communicates with the top of the vacuum tank 1 through the pipe 12, so that when the vacuum within the tank attains a predetermined degree the air or other fluid within said bellows is exhausted, causing the same 110 to contract and close the valve 24.

The self-closing valve 6 embodies a valve

plug 29, a resilient bellows 30 connected to the valve stem to actuate the valve plug 29, and a chamber 31 in which the bellows 30 is operably-mounted. The chamber 31 communicates with the pipe 16, so that when air under pressure flows therethrough it enters the chamber 31 and compresses the bellows 30, thus unseating the valve 29.

The valve 11 is similar in construction to the valve 6, excepting that its valve plug 33 is located above instead of below its seat. Thus when the bellows 34 is compressed by air under pressure entering the chamber 35, the valve plug 33 is seated instead of opened.

The thermostat 18 may be of any suitable form. In Fig. 8, of the drawings I have shown it consisting of a body 37 having an inlet duct 38 communicating with the pipe 15, and an outlet duct 39 communicating with the pipe 16. The inlet duct 38 is controlled by a valve 40 pivotally-connected at one end to a lever 42, the opposite end 43 of which is enlarged and is held by a spring against a diaphragm 44, which constitutes a portion of one wall of a duct 46, one branch of which communicates with the duct 38 and another with a leak port 47. The leak port 47 is controlled by a valve 49 loosely connected to the lever 42. The body 37 has an expansible member 50 which is fixed at one end to said body and projects into the tank 1. A glass rod or tube 51, or other element, capable of less expansion or contraction than the member 50 when subjected to variations in temperature, is held at its inner end against the inner end of the member 50 by a coil spring 53 and is connected at its outer end to a lever 54, bearing at one end against a spring 55 and at its opposite against a lever 56 connected to the valve 49. By loosely connecting the valve 49 to the lever 42, these parts are free to operate independently of each other, the valve 49, to open and close the leak port 47, and the lever 42 to actuate the valve 40. A spring 59 pressing against the lever 56, causes the same, when relieved of the pressure of the lever 54, to close the valve 49. The temperature in the vacuum tank 1 is indicated by a thermometer 19 and the water level in said tank is indicated by a glass gage 20. A drain pipe 21 leads from the lower portion of the tank 1 and has a check valve 22, which opens outwardly and permits the water to escape from the tank.

Assuming that all of the hand controlled valves are open the operation is substantially as follows: The governor 10 and the valve 11 being self-opening allow steam to enter the tank 1 and expel the air therefrom through the drain pipe 21. When the steam has raised the temperature in the tank 1 to a predetermined degree, the expansive element 50 elongates and permits the spring 53 to move the element 51 inward to the position

disclosed by Fig. 8. This action, through the intermediacy of the levers 54 and 56, opens the valve 49 and permits a portion of the air to leak from the duct 46 through the port 47. This relieves the diaphragm 44 of sufficient pressure to allow the spring 45 to move the lever 42 to position to open the valve 40, thus permitting air under pressure to flow from pipe 15 into pipe 16, which conducts it to the chambers 31 and 35 of the valves 6 and 11, the respective bellows 30 and 34 of which are thereby compressed, the bellows 31 opening the valve plug 29 to admit water to the tank 1 and the bellows 34, closing the valve plug 33 to shut off the steam from said tank 1. As the comparatively cold water enters the tank 1 it is sprayed about and condenses the steam in said tank, thereby producing a vacuum. This vacuum draws the air from the heating system through the pipe 2 and reduces the pressure in the bellows chamber of the governor 10, allowing the bellows 25 to seat the valve plug and completely shut off the flow of steam to the tank 1. When the vacuum in the tank 1 and the pipe E is lowered to a predetermined point the expansive element 50 contracts and pushes the element 51 outward, thus allowing the spring 59 to close the valve 49 and cut off the flow of air through the leak port 47. The pressure in the duct 46 then increases and forces the diaphragm 44 outwardly, causing it to move the lever 42 to position to close the valve 40 and shut off further flow of air through the pipe 16. The air under pressure in said pipe 16, then leaks out around the loosely fitting stem of the valve 40 and allows the bellows 30 and 34 to expand, the bellows 30 closing the valve 6 and thus shutting off the water, and the bellows 34 opening the valve 11 to allow steam to flow therethrough to the tank 1.

From the foregoing description it will be understood that steam and water are alternately introduced into the tank to intermittently produce a vacuum therein for the purpose of exhausting the air from the vacuum line E, and these cycles of operation continue automatically until manually checked by closing the valves 5 and 9.

While I have shown and described the preferred form of my invention, I reserve the right to make such changes in the construction, combination and arrangement of parts as properly fall within the spirit and scope of the claims.

Having thus described my invention, what I claim and desire to secure by Letters Patent, is:

1. In an apparatus of the character described, a vacuum tank, means for alternately conducting fluids of unequal temperature to said tank to create a vacuum therein, automatic valves for controlling the flow

of said fluids to the tank, means controlled by the temperature in the tank for actuating said valves, and a pressure operated valve communicating with the vacuum tank to admit steam when the pressure exceeds a predetermined point and adapted to partly control the flow of one of the fluids to the tank.

2. In an apparatus of the character described, a vacuum tank, steam and water connections leading to said tank, valves for controlling said steam and water connections, fluid under pressure for actuating said valves, a thermostatic device projecting into

the vacuum tank and arranged to control 15 the flow of fluid under pressure to the valves, a pressure operated valve to coact with one of the valves in controlling the flow of steam to the vacuum tank, and a connection between said pressure operated valve 20 and the vacuum tank, for the purpose specified.

In testimony whereof I affix my signature, in the presence of two witnesses.

JOSEPH H. BRADY.
